DETROIT TYPOMARKER COMPANY, OF DETROIT, MICHIGAN, A CORPORATION OF
MICHIGAN.

STAPLING MECHANISM FOR PIN-TICKETING MACHINES.

1,019,924.

Specification of Letters Patent. Patented Mar. 12, 1912.

Application filed February 19, 1906. Serial No. 301,814.

To all whom it may concern:

Be it known that I, BURTON W. SCOTT, a citizen of the United States, residing at Detroit, in the State of Michigan, have invented certain new and useful Improvements in Stapling Mechanism for Pin-Ticketing Machines, of which the following is a description, reference being had to the accompanying drawings, forming a part of this specification.

The present invention relates primarily to that class of machines intended for use in automatically attaching to samples of goods or articles of wearing apparel, tags or tickets with printed matter thereon, usually comprising the name of the concern handling the goods, the size, and the price or such other data as may be useful in the retailing of the merchandise. Such machines are designed to supplant the fastening of tags or tickets to goods by hand and the penciling of memoranda on the tickets. This manual process is not only slow and expensive but the pencil marks put upon the tickets if not illegible from the start become so in a short time with the handling of the goods.

The automatic machine performs all of the functions before performed by hand and requires merely the application of power and the proper guiding of the work. The tags or tickets are printed on a continuous strip of paper or card-board fed intermittently and wire for staples is correspondingly fed and a length thereof cut off in each operation of the machine and formed into a staple. The machine cuts from the continuous strip of paper or card-board a printed tag or ticket at each operation and the staple formed in each operation of the machine is driven through the tag or ticket. If such tag or ticket is to be fastened to the goods the machine is adjusted to clench the ends or legs of the staple after they have passed through the tag and the goods. If on the other hand it is desired to simply turn out stapled tags or tickets then the machine is adjusted so that the ends of the staple will not be turned back. Of course when attaching the staples to the goods by the use of the machine it is not essential that the staple pass through the tag. It might pass on

either side of the same in such close engagement with the edges thereof as to insure its being held securely in place.

Machines of the character indicated have been used to some extent in commercial establishments and their labor-saving capabilities demonstrated but it is believed there is considerable room for improvement in the character of the work done by such machines as well as in the character of construction and assemblage of parts.

The present invention aims to work improvements in such respects so that an easier running machine may be had and one which will do the work of printing, staple-forming and staple-driving with greater smoothness and despatch than machines heretofore produced. The parts making up the machine are simplified and adapted to a more compact and practical assemblage and the mechanical movements employed are such as to economize power and produce a perfect coöperation in the running of the machine.

The invention also aims to greatly simplify the arrangement whereby the machine may be converted from one which fastens the tags or tickets to the goods by a clenching process to one which simply turns out tags or tickets with unclenched staples. A single adjustment quickly made suffices in the present invention to effect this conversion. Finally the machine is considerably quickened in operation so that its output is increased.

With the above mentioned and other incidental objects in view the invention consists in certain novel features of construction and combinations of parts the essential elements whereof are recited in the appended claims and a preferred form of embodiment illustrated in the accompanying drawings and specifically described in the following specification of which said drawings form a part.

Referring first to the drawings, Figure 1 thereof represents the complete machine in side elevation; Fig. 2 a similar view on a larger scale of the head of the machine with one side plate removed and a cap piece in section; Fig. 3 represents a longitudinal section of the top part of the machine on the same

scale as Fig. 2; Fig. 4 represents the same top part of the machine in front elevation with the casing in section; Fig. 5 represents a face view and an edge view of a cam piece which 5 operates the mandrel; Fig. 6 represents a horizontal section taken on the line 6—6 of Fig. 2 and looking down, a fragment of the cap piece being left with some parts in elevation thereabove; Fig. 7 represents a 10 cross-section taken on the line 7—7 of Fig. 2; Fig. 8 represents a section taken on the line 8—8 of Fig. 2; Figs. 9, 10 and 11 are views illustrating the steps in the process of forming and clenching a staple when fastening together the ticket and the goods; 15 Fig. 12 is a similar view illustrating the stapling of a tag or ticket without clenching; and Fig. 13 represents a tag or ticket printed and attached to a piece of goods by 20 the machine.

The construction of the machine illustrated in the above described drawings is as follows: The reference numeral 2 designates a supporting column at the top of which is 25 a casing 3 of substantially cylindrical form preferably having removable side plates. This cylindrical head or casing is squared off at the top to receive a work plate 4 which will come flush with the upper surface of 30 the work table when the machine is in place. Above the said work plate is a cap piece 5 which covers all except a limited portion of the work plate at the front. The staple cutting, forming and driving mechanism is 35 located below this work plate within the cylindrical head 3 and the formed staple is projected up through a suitable opening in said work plate in front of the cap piece 5. The type for printing the tag or ticket is 40 also carried within the cylindrical casing and works up through another opening in the work plate 4 beneath the cap-piece 5. The printed ticket strip is fed out from under the cap-piece 5 in a channel of the 45 work plate 4 and over the opening in the front part of the latter up through which the staple is driven. The only part of the stapling mechanism which is above the work-plate is a clencher head 6 which over- 50 hangs that part of the work-plate through which the staple is projected.

Having thus indicated generally the organization of the machine a detailed description of the mechanism will ensue. A 55 shaft 7 (Fig. 7) is mounted to turn in bearings in the side plates of the cylindrical casing 3, said shaft extending axially of said casing and having loosely mounted upon it a sprocket wheel 8 with the teeth of which 60 engages a sprocket chain 9 (Fig. 1). This sprocket chain is coupled at one end to a treadle 10 in the form of a lever working through slots in the base of the column 2 and pivoted at one end between lugs on the 65 latter. The other end of the sprocket chain

is connected with a coiled spring 11 fastened to a lug on the inside of the column. This arrangement will be seen to provide for turning of the sprocket wheel in one direction by foot pressure on the treadle 10 and in the opposite direction by the coiled spring 11 which is of the retractile order. The sprocket wheel has compounded with it an arm 12 (Figs. 1 and 7) which extends between stops 13 on the casing to limit the oscillatory movement of the wheel. On the side opposite that where said arm 12 is located the sprocket wheel is formed with a laterally projecting annular flange 14 which at diametrically opposite points (Fig. 3) is 70 recessed to form right-angled notches 15. Alongside of the sprocket wheel on the same side as said flange there is mounted upon the shaft 7 and affixed thereto a disk 16 (Fig. 7) which carries a pivoted dog or 75 pawl 17 pressed by a spring 18 into engagement with the inner wall of the flange 14. This construction will be seen to provide for actuation of the disk 16 whenever the confronting side of one of the notches 15 drives 80 against the end of the dog or pawl 17. This will take place when the sprocket wheel is being turned by foot pressure on the treadle in the direction of the arrow (Fig. 3) but it will be observed that the disk 16 can at 85 any time advance in the same direction independently of the sprocket wheel. The presence of two notches 15 diametrically opposite each other of course indicates that the movements of the disk 16 under actuation of the sprocket wheel are divided, first one notch engaging with the dog in one operation of the machine and then the other notch engaging with the dog in the next 90 operation of the machine. The reasons for this will become apparent as the description proceeds. The disk 16 carries on the side opposite the dog 17 a pair of rollers 19 located at diametrically opposite points and 95 freely rotatable upon studs fastened in the disk. These rollers lie between the confronting horizontal edges of two vertical slides 20 and 21 (Fig. 3) and it will be seen that when the axes of the two rollers are in a horizontal plane the said confronting 100 edges of the two slides approach as near as the construction under any adjustment will permit and that by turning the disk in the direction of the arrow in Fig. 3 the two rollers with their supporting disk act as a 105 spreader to force these confronting edges of the slides away from each other. It will further be apparent that after the rollers have passed a point where their axes are in 110 vertical plane, power applied to turn the disk in the direction of the arrow becomes 115 nil so far as a separation of the confronting edges of the slides is concerned and these edges may again approach. A retractile 120 spiral spring 22 connects the two slides 20 125 and 21. The other end of the spiral spring 22 connects with the outer end of the 130

and 21 tending always to draw them together and the slides normally bear against opposite portions of the rollers 19, and in the operation of the machine the turning of 5 the sprocket wheel through the application of foot pressure on the treadle causes one of the notches 15 to engage with the end of the dog or pawl 17 and the disk 16 to be carried through a quarter turn or a fraction beyond 10 by the thrust of one side of one of the notches against the end of the dog. As soon as the axes of the rollers 19 pass the vertical plane the spring 22 draws the slides together revolving the disk 16 and bringing 15 the rollers again to their horizontal position. It will thus be seen that after the slides have been spread apart they can come together again while the sprocket wheel is still in a forward position. This is availed 20 of to insure an instantaneous separation of the ticket and wire cutting knives and also of the staple-forming and clenching devices so that the strip and wire feed for the next 25 operation will not be obstructed by any of these parts. Of course it is essential that the disk 16 turn only in one direction, and in order to prevent its turning backward its periphery is formed with ratchet teeth 16^a and a spring pawl 16^b is suitably mounted to 30 engage the same as shown in Fig. 3.

As the spreading apart of the confronting edges of the slides 20 and 21 is the result of an application of power which must also 35 perform the work of cutting, printing and stapling it is necessary that there be a transposition of confronting parts of the two slides so that the spreading apart of the aforesaid confronting edges will be accompanied by a coming together of other parts 40 of the slides. The slide 20 works up and down between guide-ribs 23 on the casing and is confined by screws entered through slots in said slide and the slide 21 is secured to a guide-rod 24 which extends up through 45 part of the slide 20 and thence up through the top of the machine, the cap-piece 5 being bushed for the purpose. The clencher head 6 is secured to this rod 24, which rod virtually forms part of the slide 21. It will 50 thus be seen that the clencher head and the slide 20 will approach as the lower part of the slide 21 and the slide 20 separate. The slide 20 carries on its upper side a knife block 25 with inclined knife blade 26 to work 55 through an opening 27 in the work plate 4 and coöperate with a shearing effect with a fixed knife 28 secured in a recess in the underside of the cap-piece 5. These knives sever the ticket strip. The knife block 25 60 also has an oblique cutting edge 30 at the front right-hand corner (Fig. 6) which co-operates with the oblique face of a split steel bushing 31 secured in one side of the casing 3 and through which the staple-wire 65 enters. It will thus be seen that in the

ascent of the slide 20 the ticket strip is severed and also the staple-wire, the latter being cut on an angle so as to produce a sharp pointed end on the severed ends of wire.

The knife block 25 is grooved behind the cutting edge 30 as shown at 31^a so as to provide for sharpening said cutting edge. The block 25 is also utilized as a staple-former or bender, this block being recessed at the front as shown at 32 and the recess being 75 rectangular in cross-section and continued through the face of the slide 20. The top of those portions of the block 25 utilized as a staple-former or bender is grooved transversely to receive the staple-wire which is 80 fed in through the bushing 31 and across the channel or recess 32. A mandrel in the form of a lever 33 is pivoted upon a fixed support in the casing 3 at a point (33^a) intermediate of its ends, said mandrel confronting the 85 channel or recess 32 of the staple-former and formed at its upper end to overhang said recess. This upper end takes the form of a beak as shown at 34 and normally arches the line of traverse of the staple-wire as 90 shown in Fig. 3. At a point above the pivot of the mandrel lever 33 the latter is formed with a nose 35 and at a point below the pivot with a similar nose 36. There is fastened upon the front of the slide 20 a cam plate 37 95 (Figs. 4 and 5) said plate comprising a body portion and a laterally projecting portion 38 with chamfered top and bottom edges. This cam plate is secured so as to have its lateral portion 38 project across the channel 100 or recess 32 in position to coöperate with the noses 35 and 36 of the mandrel lever 33. Normally the upper chamfered edge of the cam plate is below the nose 35 and a portion 105 of the cam plate above the lower chamfered edge engages the lower nose 36 of the mandrel lever. Thus the lower end of the mandrel lever is held outwardly and consequently its upper end or beak is projected over the line of traverse of the staple wire. 110 During the forming of the staple this condition obtains but when the staple has been formed and is to be driven the mandrel lever is rocked by the action of the upper chamfered edge against the nose 35, the lower 115 chamfered edge having meanwhile passed upwardly beyond the nose 36.

The staple driver is in the form of a bar 120 39 slidably mounted in the recess or channel 32 and grooved at its upper end to engage the central part of the staple. The sides of the channel 32 are similarly grooved as shown at 40 in Fig. 3 so that as the staple is formed its sides are driven into these grooves 125 40 and thereafter the groove in the upper end of the staple driver engages the middle portion of the staple which will thus be securely held in its proper adjustment while being driven. Of course the staple driver 130 should not act until the staple has been

formed and consequently no movement is allowed it independently of the staple former until the forming process is concluded. This staple driver is actuated through the medium of a bell crank lever pivoted at 41 to a depending lug of the slide 20, one arm 42 of the said bell crank lever extending forward and being slotted at 43 to embrace a pin or stud 44 on the lower end of the staple driver 39. The other arm 45 of said bell crank lever projects rearwardly into the path of a stud 46 on the sprocket wheel 8. Normally this stud of the sprocket wheel is about diametrically opposite the arm 45 of the bell crank lever. Thus the stud does not reach said lever until the sprocket wheel has been turned through the greater portion of its advance. Meanwhile the slide 20 is rising and the parts are so timed that instantly upon the complete formation of the staple the stud 46 and bell crank lever meet and thereupon said lever rocks and the staple driver is thrust upwardly, driving the formed staple through the opening in the work plate 4.

In order to secure a positive restoration of the bell crank to normal when the slide 20 lowers a fixed cam plate 47 is mounted in the casing 3 and the bell crank lever is equipped with a roller 48 upon a stud of a downward extension of the arm 45, said roller contacting with the cam edge of the plate 47 as the slide 20 lowers. A vertical edge of this cam plate holds the bell crank lever in its normal adjustment as clearly shown in Fig. 2. The bending or forming of the staple is of course brought about through the rise of the block 25 over which the staple wire lies, while the beak of the mandrel extends over the said wire. The mandrel is the same width as the channel 32 and is rectangular in cross-section so that by maintaining its position over the cut length of wire it will hold the central part thereof while the wire on either side is bent upwardly over the sides of the mandrel by the rise of the staple former. The operative position of the mandrel is made definite by providing on its side above the pivot a lug 49 which limits the backward movement of the upper arm of the mandrel lever by coming in contact with the plate 37. The movement of the lever in the opposite direction is limited by a shoulder 50 adjacent to the nose 36 contacting with the plate 37.

The clencher head 6 hereinbefore mentioned as secured to the upper end of the guide rod 24 is in the form of a cross head also secured to a short guide rod 51 sliding through a boss 52 of the cap piece 5. The cross head has a forwardly projecting portion 53 of tubular form constituting a holder for the clencher block or anvil 54. The latter comprises a stem 55 engaging the tubular holder 53 with capability of turning there-

in, and a knob 56 projecting above the holder and affording a convenient means for turning the clencher block or anvil. The stem of the latter is provided with longitudinal grooves or channels 57 at right angles to each other and there is mounted in a transverse opening of the holder 53 a retaining pin 58 held inwardly by a flat spring 59. This retaining pin is adapted to engage either one of the grooves or channels 57. The clencher block or anvil 54 is rectangular in cross-section and of greater length than width. When the retaining pin 58 is engaged in one of the grooves 57 the anvil is held in a position where its length lies cross-wise of the machine. When thus adjusted the anvil presents its lower face to the staple driver in such manner that the ends of a staple thrust upwardly by said driver will encounter the clenching portions of the anvil. These portions are respectively curvilinear as shown at 60 in Fig. 4 and retreat from the squared central portion 61 of the anvil face, which central portion coincides in length with that of the upper grooved face of the staple driver 39.

With the anvil adjusted so as to lie transversely of the machine as shown in Figs. 9 to 11 the ends of the staple will be turned back so as to clench the tag or ticket to the goods. In these views *a* designates the staple, *b* the tag and *c* the goods. By turning the anvil to a position at right angles to that illustrated in these figures the machine will be converted into one for simply securing staples to tags without clenching the same for it will be seen that when so adjusted the anvil no longer presents its curved clenching portions 60 to the ends of the staple but the latter may pass upwardly on either side of the anvil. The width of the latter is substantially the same as the length of the central portion of the staple as illustrated in Fig. 12 so that the ends or legs of the staple will not be affected when the staple is driven upwardly through the tag. Under this adjustment the anvil simply serves as a means for holding down the tag while the staple is driven through it. It will thus be seen that by a very simple adjustment the machine can be converted from one for clenching tags to goods into one for turning out tags with staples run through them unclenched.

The means for printing upon the ticket strip are of the following description: The upper side of the slide 20 is constructed to receive type chases, one of which, 62, is permanently mounted upon the slide, this type chase consisting simply in a grid for subdividing the ticket or tag by printing thereon cross-lines within a border line. This grid is shown at 63 in Fig. 6 and may be secured upon the slide 20 in any suitable manner. The subdivision at one end of the grid

is preferably made somewhat larger than the others for the purpose of receiving a plate or die (not shown) with the name of the concern using the machine. The other 5 type chase 65 is removably mounted upon the slide 20, being adapted to slide in and out of a channel provided for it in the top of the latter and confined therein by a latch of the latter and confined therein by a latch 10 plate 66 pivoted at 67 to the slide 20 and having a handle 68 by which to lift it. The type chase 65 comprises a body portion and a number of partitions 70 channeled to receive type which are ribbed for engagement with the channels. (See Fig. 6.) This 15 type chase is for the purpose of accommodating various arrangements of type for printing the desired data upon the ticket between the lines marked thereon by the grid 63, such data for example as the number, 20 the size and the price of the goods. (See Fig. 13.) By arranging for printing on the under-side of the ticket strip the simplest construction in type chases is made possible, it not being necessary to provide any special construction to hold the type from dropping out of the chase as in the case of inverted type chases. The ticket strip is designated by the letter *d* and occupies a longitudinal channel 72 in the work-plate 4, the 25 latter being cut out over the type-chases so that the latter may rise through the work-plate and make impressions upon the ticket strip.

The cap-piece 5 is provided in its under-surface with an impression block 73 extending over both type-chases and adapted to cooperate with the same in producing the impressions upon the ticket-strip. Inking ribbons 74 and 75 are employed, these ribbons 30 passing through slots between the work-plate 4 and the sides of the casing 3, one ribbon being allotted to each type-chase and the ribbons being preferably of different colors. The ribbons are carried upon reels 40 45 50 55 60 65 journaled in brackets 77 projecting from opposite sides of the cap-piece 5. The two reels at one side of the cap-piece are made as a unitary structure and so of the two drums at the opposite side of said cap-piece, so that a single actuating device will be sufficient to feed both ribbons. This actuating device comprises ratchet teeth 78 secured in one side-piece of one of the compound drums and an arm 79 pivoted concentrically with the drum and carrying a pawl 80 spring-pressed into engagement with the ratchet teeth. The arm 79 is formed at its outer end with a cam slot 81 which embraces a pin 82 projecting from the clencher cross-head 6. In the vertical reciprocations of the latter a camming action is effected between this pin 82 and the slot 81 with the result that the arm 79 is vibrated with each reciprocation of the cross-head and thereby the drum is turned a step with each operation of the

machine so that both inking ribbons are moved slightly. A retaining pawl 84 prevents backward movement of the take-up drum but may be displaced when the ribbons have been wound upon said drum to the 70 limit and it is desired to rewind them upon the opposite drums.

By the use of inking ribbons in place of pads or rollers and arranging them in the manner above described very clear and legible impressions are insured and uniformity 75 in the character of the impressions.

The ticket strip and staple wire—the latter being designated by the letter *e*—are fed through the same instrumentalities as follows: Upon a shaft 85, journaled in bearings on the side-plates of the casing 3, there are secured a roller 86 within said casing and having a roughened periphery and a roller 87 outside of said casing and having 80 a grooved periphery. The side plates of the casing 3 have upwardly projecting portions 88 at the rear and in openings therein are mounted circular disks 89 and in these disks there is eccentrically journaled a shaft 90 carrying a roller 92 in juxtaposition to the grooved roller 87 and a roller 91 in juxtaposition to the roller 86. The roller 91 is preferably faced with rubber and is designed to coöperate with the roller 86 in 95 feeding the ticket strip *d*. The roller 92 co-operates with the roller 87 to feed the staple wire, the groove in the roller 87 being sufficiently roughened to insure a grip upon the wire. The roller 91 may be fixed to the 100 shaft 90 and the roller 92 loosely mounted thereon but the particular manner of mounting these rollers is of course a matter of choice and can be varied so long as their co-operation is insured to properly feed the 105 ticket strip and wire. The disks 89 carrying the shaft 90 eccentrically, afford means for moving the rollers 91 and 92 into and out of coöoperative relation with the rollers 86 and 87 in a well-known manner. These 110 disks have compounded with them arms 93 which are united by a handle 94 which is connected by a retractile spring 95 with the cap piece 5 so as to normally hold the pairs of rollers in contact. The contact is of 115 course a yielding one so as to accommodate the ticket strip and the staple wire and in order to feed the strip and wire it will be seen that it is only necessary to rotate one of the rollers step by step with each operation of the machine.

It is desirable to effect the advance of the ticket strip and the staple wire upon the return of the treadle and to this end the following connection is used between the 125 sprocket wheel 8 and the roller 86 to turn the latter upon the reverse or backward rotation of said sprocket wheel. A link 96 is coupled to a crank-arm 8^a compounded with said sprocket wheel and extends to an arm 130

97 loosely mounted upon the shaft 85, the link and arm being pivotally connected and the same pivot serving to support a pawl 98 spring-pressed into engagement with a 5 ratchet wheel 99 secured to the roller 86. It will be seen that during the descent of the treadle 10 and the consequent forward rotation of the sprocket wheel 8 the pawl 98 is carried back over a tooth of the ratchet 10 wheel 99 so that the feed rollers remain stationary during this part of the operation of the machine. However, when the treadle is released and the spring 11 turns the sprocket wheel 8 backward the pawl 98 will 15 act against a tooth of the ratchet wheel 99 and turn the feed rollers so as to advance the ticket strip and the wire. The ticket strip is preferably carried in a roll at one side of the machine within a casing 100 20 (see Fig. 1) and thence runs to the bight of the rollers 86 and 91 after passing through a slot in the rear of the casing 3. As heretofore explained this ticket strip where it extends beyond the feed rollers lies 25 in a channel of the work plate 4. The feed motion of the rollers is sufficient to advance the strip the length of a tag or ticket, projecting this much of the strip over the front part of the work plate so that the knife 26 30 rising through the opening 27 in said work plate will sever this advanced portion of the strip by coöperation with the stationary knife 28 and the staple driver 39 rising to an opening 101 in said work plate 4 will 35 drive the staple through the severed tag or ticket which is held down by the anvil 54. The staple wire is carried in a roll within a casing 102 above the casing 100 and passes therefrom to the bight of the 40 rollers 87 and 92 and having passed between said rollers enters a tube 103 supported on a shelf 104 projecting from one of the side plates of the casing 3. This tube after 45 describing a compound curve enters the steel bushing 31 so as to deliver the wire into the bore of said bushing as shown in Fig. 6. The motion imparted to the feed rollers as heretofore explained is sufficient to advance a length of wire properly proportioned for 50 the making of a single staple. As heretofore explained this length of wire is projected from the bushing 31 across the staple former in the groove thereof and in the rise of said staple former the wire cutter co- 55 operating with the beveled face of the hardened bushing 31 will sever the wire pointing its end.

The operation of the machine will have become more or less apparent in the course 60 of the preceding description so that it is unnecessary to repeat the same in detail. The normal condition of the machine is represented in the various figures of the drawings, except Figs. 9 to 13; the clencher block 65 or anvil is represented as leaving ample

space for the insertion of goods to be tagged which will be placed above the work table 4 and over the advanced portion of the ticket strip and the advanced length of wire which lies beneath the work plate. Pressure on the treadle 10 will result in the staple being formed and clenched in the manner hereinbefore described and the peculiarities of the driving connections are such as to cause the instant restoration of the strip and wire cutting and staple forming and clenching movable parts to normal, independently of the treadle and its immediate connections. This restoration takes place with the treadle still depressed or in other words just as the treadle reaches the limit of its downward movement the above mentioned parts are restored to their normal position automatically so that there can be no obstruction to the advance of the ticket strip and wire which is to take place upon the rise of the treadle. Therefore no matter how quickly the treadle may be operated the way is bound to be clear for the advance of the strip and wire.

It will now be seen that the construction above described is well calculated to thoroughly fulfil the various objects primarily stated. However, it is to be understood that this construction may be considerably modified without departing from the spirit and scope of the invention.

Different colored inking ribbons may be employed or a single polychrome ribbon and the feed mechanism therefor may be 100 made automatically reversible.

What is claimed is:

1. In a machine of the character described the combination of complementary members movable toward and from each other and having confronting stapling portions and transposedly confronting actuator-portions, and an actuator in the nature of a spreader interposed between said latter portions; substantially as described.

2. In a machine of the character described the combination of complementary members movable toward and from each other and having confronting stapling portions and transposedly confronting actuator-portions, means yieldingly advancing said latter portions toward each other, and an actuator in the nature of a spreader interposed between said actuator portions and movable to separate the same and then by continued movement permit them to approach; substantially as described.

3. In a machine of the character described the combination of complementary members movable toward and from each other and having confronting stapling portions and transposedly confronting actuator-portions, means yieldingly advancing said latter portions toward each other, an actuator in the nature of a spreader interposed between said 125

- actuator portions and means for operating said spreader with provision for permitting continued movement thereof independent of the operating means; substantially as and for the purpose described.
4. In a machine of the character described the combination of complemental members 5
slidable toward and from each other and having confronting stapling portions and transposedly confronting actuator-portions, and an actuator in the nature of a spreader 10
interposed between said latter portions; substantially as described.
5. In a machine of the character described 15
the combination of complemental members slidable toward and from each other and having confronting stapling portions and transposedly confronting actuator-portions, means yieldingly advancing said latter portions toward each other and an actuator in the nature of a spreader 20
interposed between said actuator-portions and movable to separate the same and then by continued movement permit them to approach; substantially as described.
6. In a machine of the character described 25
the combination of complemental members slidable toward and from each other and having confronting stapling portions and transposedly confronting actuator-portions, means yieldingly advancing said latter portions toward each other, an actuator in the nature of a spreader 30
interposed between said actuator-portions and means for operating said spreader with provision for permitting continued movement thereof independent of the operating means; substantially as and for the purpose described.
7. In a machine of the character described 35
the combination of complemental members movable toward and from each other and having confronting stapling portions and transposedly confronting actuator-portions, and an actuator in the nature of a pivotal 40
spreader interposed between said latter portions; substantially as described.
8. In a machine of the character described 45
the combination of complemental members movable toward and from each other and having confronting stapling portions and transposedly confronting actuator-portions, means yieldingly advancing said latter portions toward each other, and an actuator in the nature of a pivotal spreader interposed 50
between said actuator-portions and movable to separate the same and then by continued movement permit them to approach; substantially as described.
9. In a machine of the character described 55
the combination of complemental members movable toward and from each other and having confronting stapling portions and transposedly confronting actuator-portions, means yieldingly advancing said latter portions toward each other, an actuator in the nature of a pivotal spreader interposed 60
between said actuator-portions and movable to separate the same and then by continued movement permit them to approach; substantially as described.
10. In a machine of the character described 65
the combination of complemental members movable toward and from each other and having confronting stapling portions and transposedly confronting actuator-portions, means yieldingly advancing said latter portions toward each other, an actuator in the nature of a spreader interposed 70
between said actuator-portions and means for operating said spreader through a one-way connection therewith.
11. In a machine of the character described 75
the combination of complemental members slidable toward and from each other and having confronting stapling portions and transposedly confronting actuator-portions, means yieldingly advancing said latter portions toward each other, an actuator in the nature of a pivotal spreader 80
interposed between said actuator-portions and means for operating said spreader through a one-way connection therewith.
12. In a machine of the character described 85
the combination of complemental members movable toward and from each other and having confronting stapling portions and transposedly confronting actuator-portions, means yieldingly advancing said latter portions toward each other, an actuator in the nature of a spreader 90
interposed between said actuator-portions and a reciprocating driver for the spreader having a one-way connection therewith.
13. In a machine of the character described 95
the combination of complemental members slidable toward and from each other and having confronting stapling portions and transposedly confronting actuator-portions, means yieldingly advancing 100
said latter portions toward each other, an actuator in the nature of a spreader interposed between said actuator portions and a reciprocating driver for the spreader having a one-way connection therewith.
14. In a machine of the character described 105
the combination of complemental members slidable toward and from each other and having confronting stapling portions and transposedly confronting actuator-portions, means yieldingly advancing 110
said latter portions toward each other, an actuator in the nature of a pivotal spreader interposed between said actuator portions and movable to separate the same and then by continued movement permit them to approach, and a reciprocating driver for the spreader having a one-way connection therewith.
15. In a machine of the character described 115
the combination of complemental members slidable toward and from each other and having confronting stapling portions and transposedly confronting actuator-portions, means yieldingly advancing 120
said latter portions toward each other, an actuator in the nature of a pivotal spreader interposed between said actuator portions, and an oscillating driver for the spreader having a one-way connection therewith.
16. In a machine of the character described 125
the combination of complemental members slidable toward and from each other and having confronting stapling portions and transposedly confronting actuator-portions, means yieldingly advancing 130
said latter portions toward each other, an actuator in the nature of a pivotal spreader interposed between said actuator portions, and an oscillating driver for the spreader having a one-way connection therewith.

scribed the combination of complementary members movable toward and from each other and having confronting stapling portions and transposedly confronting actuator-portions, means yieldingly advancing said latter portions toward each other, and an actuator in the nature of a pivotal spreader interposed between said actuator portions and engaging the same on opposite sides of its pivot, said spreader by a quarter turn bringing the stapling portions together and then by continued movement yielding to the said means for advancing the actuator portions and thus making another quarter turn; substantially as described.

16. In a machine of the character described the combination of complementary members movable toward and from each other and having confronting stapling portions and transposedly confronting actuator-portions, means yieldingly advancing said latter portions toward each other, an actuator in the nature of a pivotal spreader interposed between said actuator portions and engaging the same on opposite sides of its pivot, said spreader by a quarter turn bringing the stapling portions together and then by continued movement yielding to the said means for advancing the actuator portions and thus making another quarter turn, and a driver for the spreader having a one-way connection therewith.

17. In a machine of the character described the combination of complementary members movable toward and from each other and having confronting stapling portions and transposedly confronting actuator-portions, means yieldingly advancing said latter portions toward each other, an actuator in the nature of a spreader interposed between said actuator portions and movable to separate the same and then by continued movement permit them to approach, a driver for the spreader having a one-way connection therewith, and a wire feeding mechanism operated by said driver.

18. In a machine of the character described the combination of complementary members movable toward and from each other and having confronting stapling portions and transposedly confronting actuator-portions means yieldingly advancing said latter portions toward each other, an actuator in the nature of a spreader interposed between said actuator portions and movable to separate the same and then by continued movement permit them to approach, a reciprocating driver for the spreader having a one-way connection therewith, and a wire feeding mechanism operated by said driver on the return or back stroke of the latter.

19. In a machine of the character described the combination of complementary

members movable toward and from each other and having confronting stapling portions and transposedly confronting actuator-portions, means yieldingly advancing said latter portions toward each other, an actuator in the nature of a pivotal spreader interposed between said actuator portions and movable to separate the same and then by continued movement permit them to approach, an oscillating driver for the spreader having a one-way connection therewith, and an intermittent wire feeding mechanism operated by said driver.

20. In a machine of the character described the combination of complementary members movable toward and from each other and having confronting stapling portions and transposedly confronting actuator-portions, means yieldingly advancing said latter portions toward each other, an actuator in the nature of a pivotal spreader interposed between said actuator portions and engaging the same on opposite sides of its pivot, said spreader by a quarter turn bringing the stapling portions together and then by continued movement yielding to the said means for advancing the actuator portions and thus making another quarter turn, a driver for the spreader having a one-way connection therewith, and a wire feeding mechanism operated by the driver.

21. In a machine of the character described the combination of complementary members movable toward and from each other and having confronting stapling portions and transposedly confronting actuator-portions, and an actuator in the nature of a spreader interposed between said latter portions and comprising a pivotal support and rollers mounted thereon at diametrically opposite points.

22. In a machine of the character described the combination of complementary members movable toward and from each other and having confronting stapling portions and transposedly confronting actuator-portions, means yieldingly advancing said latter portions toward each other, and an actuator in the nature of a spreader interposed between said actuator portions and movable to separate the same and then by continued movement permit to approach, said actuator comprising a pivotal support and rollers mounted thereon at diametrically opposite points.

23. In a machine of the character described the combination of complementary members slidably toward and from each other and having confronting stapling portions and transposedly confronting actuator-portions, means yieldingly advancing said latter portions toward each other, and an actuator in the nature of a spreader interposed between said actuator portions and movable to separate the same and then by

continued movement permit them to approach, said actuator comprising a pivotal support and rollers mounted thereon at diametrically opposite points.

- 5 24. In a machine of the character described the combination of complementary members movable toward and from each other and having confronting stapling portions and transposedly confronting actuator portions, means yieldingly advancing said latter portions toward each other, and an actuator in the nature of a spreader interposed between said actuator portions and comprising a pivotal support and rollers 10 mounted thereon at diametrically opposite points, said spreader by a quarter turn bringing the stapling portions together and then by continued movement yielding to the said means for advancing the actuator portions and thus making another quarter turn, substantially as described.

25. In a machine of the character described, the combination of complementary members movable toward and from each other and having confronting stapling portions and transposedly confronting actuator-ports, means yieldingly advancing said latter portions toward each other, an actuator in the nature of a spreader interposed between said actuator portions and movable to separate the same, and means for operating said spreader with provisions for permitting continued movement thereof independent of the operating means and for 35 preventing backward movement of the spreader.

26. In a machine of the character described the combination of complementary members movable toward and from each other and having confronting stapling portions and transposedly confronting actuator-ports, means yieldingly advancing said latter portions toward each other, and an actuator in the nature of a pivotal spreader interposed 40 between said actuator portions and engaging the same on opposite sides of its pivot, said spreader by a quarter turn bringing the stapling portions together and then by continued movement yielding to the said means 45 for advancing the actuator portions and thus making another quarter turn, together with means for preventing backward turning of the spreader.

27. In a machine of the character described, the combination of a movable support or carriage, a staple former and a staple driver, both mounted thereon and wholly supported thereby but relatively movable, an actuator for the support, and 55 means carried by the latter for producing relative movement between staple former and driver and operated by the said actuator.

28. In a machine of the character described, the combination of a movable sup-

port or carriage, a staple former and a staple driver, both mounted thereon and wholly supported thereby but relatively movable, an actuator for the support, and means carried by the latter for producing 70 relative movement between staple former and driver and operated by the said actuator through engagement of a portion thereof moving oppositely to the support.

29. In a machine of the character described, the combination of a rectilinearly movable support, a staple former and a staple driver, both mounted thereon and wholly supported thereby but relatively movable, means for reciprocating said support comprising a curvilinearly movable element, and means carried by the support for producing relative movement between staple former and driver, said last named means operated by the said curvilinearly 80 movable element.

30. In a machine of the character described, the combination of a rectilinearly movable support, a staple former and a staple driver both mounted thereon and relatively movable, means for reciprocating said support comprising a curvilinearly movable element, and means carried by the support for producing relative movement between staple former and driver, said last 90 named means comprising a lever projecting into the path of an abutment on the curvilinearly movable element.

31. In a machine of the character described, the combination of a slide having 100 compounded with it a staple former, a staple driver slidably mounted in said slide, a lever pivoted on the latter and coupled to said staple driver, and a driving mechanism including means for reciprocating the 105 slide with provisions for vibrating said lever.

32. In a machine of the character described the combination of a slide having compounded with it a staple former, a 110 staple driver slidably mounted in said slide, a lever pivoted on the latter and coupled to said staple driver, and a driving mechanism for reciprocating said slide including a pivotally mounted element with an abutment 115 to act upon said lever.

33. In a machine of the character described the combination of a slide having compounded with it a staple former, a staple driver slidably mounted in said slide, a 120 lever pivoted on the latter and coupled to said staple driver, and a driving mechanism for reciprocating said slide including a pivotally mounted element with an abutment to act upon said lever for advancing the staple driver during the advance of the slide.

34. In a machine of the character described the combination of a slide having compounded with it a staple former, a staple 125

driver slidably mounted in said slide, a lever on the latter coupled to said staple driver, and a driving mechanism for reciprocating said slide including a pivotally mounted element with an abutment to act upon said lever for advancing the staple driver during the advance of the slide together with a fixed abutment for returning the lever in the return movement of the slide.

35. In a machine of the character described a reciprocating support, and a clenching block carried thereby with provisions for adjustment to operative and inoperative positions one substantially at right angles to the other.

36. In a machine of the character described, a reciprocating support, and a clenching block rotatively mounted therein and capable of assuming clenching or non-

clenching positions one substantially at right angles to the other.

37. In a machine of the character described, a reciprocating support, and a clenching block rotatively mounted therein and capable of assuming clenching or non-clenching positions one substantially at right angles to the other, together with a retainer to hold said block in either of its two adjustments.

38. In a machine of the character described, the combination with staple-driving means, of an anvil having clenching and non-clenching dimensions, and adjustable to present either dimension to the staple.

BURTON W. SCOTT.
